MACHINE FOR DELASTING BOOTS AND SHOES

Max Grune, Pirmasens, Germany, assignor to
Schön & Cie. A. G., Pirmasens, GermanyApplication September 18, 1933, Serial No. 690,004
In Germany December 30, 1932

18 Claims. (Cl. 12—15.1)

This invention relates to a machine for delasting boots and shoes. The delasting of blocked shoes, when performed by hand, is a very exhausting operation and, for this reason, recourse has been had to mechanical delasting, by means of suitable delasting machines. The machines of this kind hitherto devised have not, however, been widely used, as they are by no means a perfect substitute for hand labour and, in particular, have the disadvantage that the shoes are very easily damaged when being delasted. When these known delasting machines are used it is impossible to prevent the delasting tool from slipping on the uppers of the shoes mounted on the gripper last. The friction thus produced damages the surface of the leather, spoiling its appearance and may even destroy delicate leathers.

The problem which the present invention is intended to solve is, therefore, to provide a delasting machine which, while not having the disadvantage above referred to, will enable boots and shoes to be delasted mechanically in a satisfactory manner. According to the invention, this object is achieved, in the main, by using hydraulic operating mechanism, both for pressing the shoe mounted on the last against the delasting mechanism and also for moving the delasting tool for the purpose of stripping the shoes from the last. It is preferable to use separate hydraulic pistons, the pressure cylinders of which are at right angles to each other, for pressing the shoe against the last and for delasting it, care being taken, by the provision of suitable hydraulic passages or the like, that the pressure medium first moves the piston which presses the shoe against the last and only acts on the piston which produces the movement of the delasting tool after a definite pressure upon the shoe on the last has been attained. When hydraulic operating mechanism of this kind is employed it can be simply and satisfactorily ensured that the shoe blocked on the last is pressed against the latter before the delasting tool begins to move, with a pressure which, when the said tool begins to move, is powerful enough to render slipping of the tool on the upper of the shoe impossible.

The accompanying drawing shows, by way of example, a constructional form of machine according to the invention.

In this drawing:

Fig. 1 is a vertical section through a hydraulically operated de-lasting machine.

Fig. 2 is a view of the upper portion of the machine in another operative position and

Fig. 3 is a section taken on the line A—B in Fig. 1.

In the hollow standard 1 of the machine and on a bracket 2 is mounted a gear wheel pump 3 of the well known type of construction. Oil, or other suitable liquid, is drawn up from a sump 5 through the suction pipe 4 of this pump, which delivers it, through a force pipe 6, into a passage 7^a in a cylinder block 7, containing the principal parts of the machine.

In the upper part of the block 7 is a vertical cylindrical bore in which works a piston 8, provided, at its upper end, with a cylindrical extension 8^a, of smaller diameter, on which is mounted a sleeve 9 provided with a collar 9^a. On to the sleeve 9 is pressed a delasting tool 10, made of a yielding material, preferably rubber, said delasting tool being substantially cylindrical in shape. Against the upper end face of the delasting tool bears the outer edge of a disc 11, which is held in position by a screw 12 screwed into the end face of the extension 8^a.

Below the cylindrical bore containing the piston 8 there is provided in the block 7 a horizontal cylindrical bore in which a second piston 13 works. This piston 13 has two annular grooves 13^a and 13^b turned in it and has in its inner or rear portion an axial bore in which a ball valve is mounted. This valve consists of a ball 15, which is pressed by a piston 16 acted on by a spring 14 against a sleeve 17, which latter is constructed to form a valve seat and is screwed into the bore aforesaid in the piston 13. This bore, containing the ball valve, communicates through a passage 13^c with the annular groove 13^b. The right hand end of the same bore communicates through a vertical passage 7^d with the bore 7^a in the block 7.

To the left hand end of the piston 13 is fixed a pin 18 about which engages the lower end of a lever 20 adapted to rock on a pin 19. This lever 20 carries, at its upper end, a pin 21, upon which can be mounted a gripper last 22 with the shoe 23 blocked thereon. To the lower arm of the lever 20 is attached a tension spring 24 which tends to hold the lever 20 and, with it, the piston 13 in the right hand terminal position shown in Fig. 1.

In the lower part of the block 7 is provided a vertical bore for the reception of a reversing valve. This valve comprises a bushing 25, closed at its upper end and having within its bore, a safety valve comprising a valve seat 26, a ball 27, a bored through sliding member 28 and a pressure spring 29. The upper end of the spring 29

bears against the underside of the sliding member 28 and at its lower end against an end piece 30 which is provided with a passage 30^a and is screwed into the bore in the bush 25. The end piece 30 carries at its lower part a pin 31, about which fits one end of a lever 35 adapted to rock on a pin 34. To the other end of the lever 35 is pivoted the upper end of a rod 33 the lower end of which is connected to one end of a pedal lever 32 adapted to rock on a pin 38. To the lever 32 is attached a tension spring 36 which tends to hold the reversing valve in the terminal position shown in Fig. 1.

The bushing 25 of the reversing valve has turned in its outer surface an annular groove 25^a from which extends an axial recess 25^b axially aligned with the point at which the passage 7^a opens into the block 7. From the side of the reversing valve bore opposite to this recess there extends a passage 7^b which opens into a passage 7^c in the block 7. This passage 7^c leads from the interior of the hollow standard 1 to the horizontal cylinder containing the piston 13.

The machine operates as follows:

25 In the position of rest (shown in Fig. 1), in which the reversing valve 25 occupies its upper terminal position the oil delivered through the force pipe 6 and the passage 7^a flows round the annular groove 25^a turned in the reversing valve 30 and then passes back, through the passages 7^b and 7^c, directly to the oil sump.

Before starting the machine the last 22, carrying the shoe 23 to be de-lasted, is set up on the pin 21 of the lever 20 and then the pedal lever 32 is depressed. This results in the reversing valve 25 being moved downwards until the upper edge of the groove 25^a turned in it overlaps the lower edge of the passage 7^b, whereby return of the oil through the passages 7^b and 7^c is cut off. Consequently, the oil rises through the passage 7^a into the cylinder containing the piston 13 and forces this latter towards the left, until the heel portion of the shoe 23 is brought to bear against the rubber delasting tool 19. When 45 this movement of the piston 13 takes place the groove 13^b turned therein is brought into communication with the cylinder containing the vertical piston 8, while communication of the groove 13^a with this said cylinder is cut off. As the 50 travel of the piston 13 is limited by contact of the shoe 23 with the last tool 10, the oil pressure continues to rise until the pressure of the spring 14 is overcome and the ball 15, carrying with it the piston 16, is lifted from the valve seat at the inner end of the sleeve 17. In this way communication is established between the two cylinders containing the horizontal piston 13 and the vertical piston 8, respectively. Oil then flows through the passage 13^c and groove 13^b into the 55 vertical cylinder and causes the piston 8 and the de-lasting tool 10 to move upwards. When this movement of the lasting tool takes place the heel portion of the shoe 23 is moved upwards, in the manner shown in Fig. 2, to such an extent that a 60 light pull with the hand in the direction of the toe end suffices to remove the shoe from the last. After the shoe has been de-lasted the operator's foot is taken off the pedal 32, so that the reversing valve 25 can move back to the upper terminal position under the retractile force of the 65 spring 36. When this takes place the groove 25^a again registers with the passages 7^a and 7^c, so that the oil under pressure, which continues to be delivered through the pipe 6, can pass back, 70 without producing any effect, into the oil sump 75.

5, while the oil on the right hand side of the piston 13 can also run back into the sump through the passage 7^d.

The pressure acting on the piston 13 is thus relieved and this piston is therefore moved back into the right hand terminal position by the tension spring 24. By this return movement of the piston 13 the annular groove 13^a is again brought into communication with the vertical cylinder containing the piston 8, so that the oil under pressure can also run back out of this cylinder, by way of said groove 13^a and the passage 7^a into the oil sump, leaving said piston 8 free to descend into its lowest position under its own weight or under the action of a spring or a counterweight. 10 When the piston 13 moves back the lever 20 is, at the same time retracted into the position shown in Fig. 1, so that it is ready for the reception of a fresh last.

In order that a predetermined maximum pressure may not be exceeded while the machine is in operation, there is provided in the reversing valve 25 a passage 25^c, which connects the recess 25^b with the internal bore of the valve. As soon as any unforeseen excess of pressure develops the 20 oil pressure acting on the ball 27 overcomes the force of the spring 29 and the ball 27 is accordingly raised from its seat 26. The oil then runs through the bore or passage in said seat 26, through another bore in a sliding member 28, 30 through the passage 30^a in the end piece 30 and thus back into the oil sump 5.

In order to limit the upward movement of the piston 8 an overflow pipe 37, leading back into the hollow standard 1 is connected to the cylinder in 35 which this piston works. If the operator attending the machine neglects to take his foot off the pedal 32 at the proper time the piston 8 continues to move until its lower face reaches the level where the pipe 37 enters the cylinder and, 40 as soon as this point is reached, the oil escapes into said pipe and flows therethrough back into the oil sump 5. Consequently, no further upward movement of the piston 8 can take place.

The de-lasting tool 10, preferably made of soft 45 rubber, is provided, on its periphery, with a number of longitudinal flutes or channels 10^a, the cross sectional form of which is adapted to the shape of the heel portion of the particular shoe to be delasted. Accordingly, by rotating the said 50 tool, it can be brought into a position in which the maximum amount of surface contact is afforded between the shoe and the particular flute or channel 10^a thus selected. The specific pressure (pressure per unit area) on the leather is thus reduced to a minimum, so that the leather is protected from injury to the greatest possible extent. In some cases the flutes 10^a may be so shaped that they conform to the shape of the heel portion of the shoe not only in horizontal section but also in vertical section; in this way a 55 still greater reduction in the specific surface pressure can be obtained.

The above described hydraulic mechanism for 60 pressing the shoe to be delasted against the de-lasting tool and for shifting the said tool affords the special advantage that, in a certain measure, the forces required for the de-lasting operation adjust themselves automatically according to the grip with which the shoe holds on to the last so that very satisfactory delasting of the shoe is effected. In the constructional arrangement of the 65 hydraulic mechanism care is taken that the pressure with which the shoe is pressed against the tool always bears a definite relationship to the 70 75.

force required for delasting. This relationship or ratio which can easily be ascertained by practical tests, corresponds to the ratio between the effective piston surface of the vertical piston 8 and that of the horizontal piston 13. A shoe which fits tightly on to the last will, accordingly, be subjected to a greater pressure than one which fits less tightly, while, on the other hand the shoe will not be more heavily pressed than is just necessary for delasting. Slipping of the delasting tool over the upper is prevented by the vertical movement of the tool beginning only when the necessary pressure against the last has been obtained.

15 I claim:—

1. In a machine for de-lasting boots and shoes, in combination with the machine frame, a support for a last movably arranged on said frame and on which the shoe to be de-lasted is mounted, a de-lasting tool carried by said frame and movable relatively to said support and the last carried thereby, hydraulic means for pressing the last against the de-lasting tool, and hydraulic means for moving said tool relatively to said

25 last for the purpose of stripping the shoe from the last.

2. In a machine for de-lasting boots and shoes, in combination with the machine frame, a support for a last movably arranged on said frame and on which the shoe to be de-lasted is mounted, a de-lasting tool carried by said frame and movable relatively to said last, two hydraulic pressure cylinders arranged at right angles to each other on said frame, and hydraulic pistons working in said cylinders, said pistons being connected with said support and tool and adapted to press the last carried thereby against the tool and to move said tool relatively to said last for the purpose of stripping the shoe from the last.

40 3. In a machine for de-lasting boots and shoes, in combination with the machine frame, a support for a last movably arranged on said frame and on which the shoe to be de-lasted is mounted, a de-lasting tool carried by said frame and movable relatively to said last, two hydraulic pressure cylinders arranged at right angles to each other on said frame, hydraulic pistons working in said cylinders, said pistons being connected with said support and tool and adapted to press the last carried thereby against the tool and to move said tool relatively to said last for the purpose of stripping the shoe from the last, and means adapted to hydraulically connect said cylinders with each other so that the piston, which presses the support and the last carried thereby against the tool, is first moved by the pressure medium, while movement of the piston connected to the de-lasting tool takes place only after a definite pressure has been attained.

60 4. In a machine for de-lasting boots and shoes, in combination with the machine frame, a support for a last movably arranged on said frame and on which the shoe to be de-lasted is mounted, a delasting tool carried by said frame and movable relatively to said last, two hydraulic pressure cylinders arranged at right angles to each other on said frame, hydraulic pistons working in said cylinders, said pistons being connected with said support and tool and adapted to press the last carried by the support against the tool and to move said tool relatively to said last for the purpose of stripping the shoe from the last, and a supply pipe for the pressure medium communicating with the cylinder of the piston which

presses the last against the tool and passages provided on said supply pipe and adapted, when said piston moves, to establish communication between the two pressure cylinders.

5 5. In a machine for de-lasting boots and shoes, in combination with the machine frame, a support for a last movably arranged on said frame and on which the shoe to be de-lasted is mounted, a de-lasting tool carried by said frame and movable relatively to said last, two hydraulic pressure cylinders arranged at right angles to each other on said frame, hydraulic pistons working in said cylinders, said pistons being connected with said support and tool and adapted to press the last carried by the support against the tool and to move 15 said tool relatively to said last for the purpose of stripping the shoe from the last, a supply pipe for the pressure medium communicating with the cylinder of the piston which presses the last against the tool, and a valve located in said pipe 20 and being so loaded that it is adapted to establish communication between the two pressure cylinders only after a predetermined pressure has been obtained.

25 6. In a machine for de-lasting boots and shoes, in combination with the machine frame, a support for a last movably arranged on said frame and on which the shoe to be de-lasted is mounted, a de-lasting tool carried by said frame and movable relatively to said last, two hydraulic pressure cylinders arranged at right angles to each other on said frame, and hydraulic pistons working in said cylinders, said pistons being connected with said support and tool and adapted to press the last carried by the support against 30 the tool and to move said tool relatively to said last for the purpose of stripping the shoe from the last, the effective areas of the two pistons being such that the pressure exerted in pressing against the last bears a definite and constant 35 ratio to the force exerted on the shoe by the movement of the de-lasting tool.

40 7. In a machine for de-lasting boots and shoes, in combination with the machine frame, a support for a last movably arranged on said frame and on which the shoe to be de-lasted is mounted, a de-lasting tool carried by said frame and movable relatively to said last, two hydraulic pressure cylinders arranged at right angles to each other on said frame, hydraulic pistons working in said cylinders, said pistons being connected with said support and tool and adapted to press the last carried by the support against the tool and to move said tool relatively to said last for the purpose of stripping the shoe from the last, and a liquid pump common to both cylinders and adapted to deliver the pressure medium to both cylinders.

55 8. In a machine for de-lasting boots and shoes, in combination with the machine frame, a support for a last movably arranged on said frame and on which the shoe to be de-lasted is mounted, a de-lasting tool carried by said frame and movable relatively to said last, two hydraulic pressure cylinders arranged at right angles to each other on said frame, hydraulic pistons working in said cylinders, said pistons being connected with said support and tool and adapted to press the last carried by the support against the tool and to move said tool relatively to said last for the purpose of stripping the shoe from the last, and an overflow pipe connected to the pressure cylinder of the piston which moves the de-lasting tool and adapted to limit the movement of said piston. 60

9. In a machine for de-lasting boots and shoes, in combination with the machine frame, a support for a last movably arranged on said frame and on which the shoe to be de-lasting is mounted, a de-lasting tool carried by said frame and movable relatively to said last, two hydraulic pressure cylinders arranged at right angles to each other on said frame, hydraulic pistons working in said cylinders, said pistons being connected with said support and tool and adapted to press the last carried by the support against the tool and to move said tool relatively to said last for the purpose of stripping the shoe from the last, a liquid pump common to both cylinders, a sump for the liquid to be delivered to the pump, means connecting said pump with the sump and the cylinders respectively, and a reversing valve provided in connection with said means adapted to permit, in one position, the pressure medium to run back without exerting any action into the sump and in the other position to cut off the path of return flow and means for controlling said valve.
10. In a machine for de-lasting boots and shoes, in combination with the machine frame, a support for a last movably arranged on said frame and on which the shoe to be de-lasting is mounted, a de-lasting tool carried by said frame and movable relatively to said last, two hydraulic pressure cylinders arranged at right angles to each other on said frame, hydraulic pistons working in said cylinders, said pistons being connected with said support and tool and adapted to press the last carried by the support against the tool and to move said tool relatively to said last for the purpose of stripping the shoe from the last, a liquid pump common to both cylinders, a sump for the liquid to be delivered to the pump, means connecting said pump with the sump and the cylinders respectively, a reversing valve provided in connection with said means adapted to permit, in one position, the pressure medium to run back without exerting any action into the sump and in the other position to cut off the path of return flow, and a safety valve located within the reversing valve adapted to automatically open when the pressure of the pressure medium exceeds a predetermined maximum value, thereby permitting said pressure medium to flow back directly to the sump and means for controlling said reversing valve.
11. In a machine for de-lasting boots and shoes, in combination with the machine frame, a support for a last movably arranged on said frame and on which the shoe to be de-lasting is mounted, a de-lasting tool carried by said frame and movable relatively to said last, hydraulic means for pressing the last against the de-lasting tool, and hydraulic means for moving said tool relatively to said last for the purpose of stripping the shoe from the last, said de-lasting tool comprising a substantially cylindrical member of yielding material.
12. In a machine for de-lasting boots and shoes, in combination with the machine frame, a support for a last movably arranged on said frame and on which the shoe to be de-lasting is mounted, a de-lasting tool carried by said frame and movable relatively to said last, hydraulic means for pressing the last against the de-lasting tool, and hydraulic means for moving said tool relatively to said last for the purpose of stripping the shoe from the last, said de-lasting tool comprising a substantially cylindrical member of yielding material.
13. In a machine for de-lasting boots and shoes, in combination with the machine frame, a support for a last movably arranged on said frame and on which the shoe to be de-lasting is mounted, a de-lasting tool carried by said frame and movable relatively to said last, hydraulic means for pressing the last against the de-lasting tool, and hydraulic means for moving said tool relatively to said last for the purpose of stripping the shoe from the last, said de-lasting tool comprising a substantially cylindrical member of yielding material and being provided on its external surface with shaped channels conformed to the shape of the heel portion of the shoe to be de-lasting.
14. In a machine for de-lasting boots and shoes, in combination with the machine frame, a support for a last movably arranged on said frame and on which the shoe to be de-lasting is mounted, a de-lasting tool carried by said frame and movable relatively to said last, hydraulic means for pressing the last against the de-lasting tool, and hydraulic means for moving said tool relatively to said last for the purpose of stripping the shoe from the last, said de-lasting tool comprising a substantially cylindrical member of yielding material and being provided on its external surface with a plurality of differently shaped channels conforming to the shape of the heel portions of the different shoes to be de-lasting, and means for adjusting said tool so that the said channels can be selectively used as surfaces for pressing the shoe against the last.
15. A machine for de-lasting boots and shoes comprising a support for a last movably arranged and on which the shoe to be de-lasting is mounted, a de-lasting tool movable relative to said support and the last to be carried thereby, and hydraulic means for moving said support and the de-lasting tool so that the last with the shoe thereon is pressed against the tool and the tool is moved relative to the last to strip the shoe from the last.
16. A machine for de-lasting boots and shoes comprising a frame, a support for a last movably mounted on the frame and on which the shoe to be de-lasting is mounted, a de-lasting tool movably mounted on the frame relative to said support and the last to be carried thereby, and hydraulic means mounted on the frame for moving said support and the de-lasting tool so that the last with the shoe thereon is pressed against the tool and the tool is moved relative to the last to strip the shoe from the last.
17. A machine according to claim 15, in which the hydraulic means includes mechanism to exert forces for the de-lasting operation which adjust themselves automatically in a definite relationship so that the shoe will be forced against the de-lasting tool in a definite ratio to the force required to de-last the shoe from the last.
18. A machine according to claim 16, in which the hydraulic means includes mechanism to exert forces for the de-lasting operation which adjust themselves automatically in a definite relationship so that the shoe will be forced against the de-lasting tool in a definite ratio to the force required to de-last the shoe from the last.

MAX GRUNE.
